RUBBER SOLE AND HEEL

Walter L. Pipes, Elizabeth, N. J., assignor to
 United States Rubber Products, Inc., New York,
 N. Y., a corporation of Delaware

Application June 13, 1936, Serial No. 85,072

6 Claims. (Cl. 36—59)

My invention relates to rubber soles and heels, and more particularly to the improvements of the anti-slipping or anti-skidding characteristics thereof by the provision of small slits in the ground engaging surfaces thereof.

It is well known that footwear having rubber heels and/or soles may become very slippery when used on wet pavements, walks, or boardwalks, particularly if the weight of the wearer is placed on a wet metal part.

I have found that the anti-slipping or anti-skidding characteristics of rubber soles and heels may be materially improved by providing a number of slits in the exposed rubber surface. Such slits may vary from a thin slit such as is formed by a knife cut without substantial removal of material to a narrow slot such as is formed by a thin saw and in which some material is removed but which is still sufficiently narrow so that the side walls engage to mutually support each other when load is applied. The presence of the thin edges of the slits provides additional traction surface, as compared with a smooth rubber surface, and also the slits provide small passageways through which the liquid or liquid film may be squeezed to permit the rubber surface to have a relatively dry contact with the underlying road or walk surface. The slits may be super-imposed on various designs of sole and heel configurations or they may be applied directly to otherwise smooth rubber surfaces.

The accompanying drawing illustrates certain present preferred embodiments of the invention, in which:

Fig. 1 is a perspective view of a combined heel and sole embodying my invention;

Fig. 2 is a plan view of a modified form of the heel and sole;

Figs. 3, 4, 5, and 6 are similar views of further modifications of the invention;

Fig. 7 is a similar view of a sole embodying my invention;

Fig. 8 is a face view of a heel embodying my invention; and

Fig. 9 is an isometric view of a heel embodying a modified form of my invention shown in Fig. 8.

Referring particularly to Fig. 1, a wear resisting surface for a footwear article is illustrated in the form of a combined heel and sole in which the ball portion 2 of the sole and the tread surface 3 of the heel are interrupted by a considerable number of small slits or incisions 5 for improving the traction qualities of the shoe to which it is attached. These incisions extend transversely entirely across the ground engaging

surfaces of the sole and heel. The transversely arranged incisions are particularly adapted to prevent back slipping of the shoe. Incisions 5 are preferably made after the footwear is vulcanized by a cutting operation, such as by a sharp knife or very thin saw which removes substantially no material. The term "incision" as used herein means a cut formed in the surface of the vulcanized rubber composition without the removal of substantially any material, with the result that the opposite walls of the incision normally engage one another. Incisions which are wider than $\frac{1}{16}$ inch remove so much of the wearing surface of the rubber that the loss of the wearing surface is not compensated for by the increased traction effect. The spacing of the incisions depends somewhat upon the thickness of the rubber to which it is applied, although a spacing range of from $\frac{1}{8}$ inch to 1 inch is contemplated. In general, the thinner the stock, the shallower and closer the incisions. A convenient depth for the initial incisions is one-third of the thickness of the stock, although the use of incisions on stock which is less than .2 inch is not recommended. For heavy service boots, such as hunting boots, miners' boots, and the like, having thick soles and heels, incisions of the order of $\frac{1}{8}$ inch in depth are quite satisfactory. It is to be understood that after the incisions originally formed are eliminated due to the wearing of the rubber, new incisions may be made in the remaining rubber. These should preferably be of a depth of approximately one-half of the remaining rubber.

As shown in Fig. 2, in the event it is desired to have a smooth appearing outer edge of the soles and/or heels, uncut margins 6 and 7 of the order of $\frac{1}{2}$ inch in width may be provided around the edges of the sole and heel portions, respectively.

Referring to Fig. 3, a combined sole and heel 8 is shown provided with longitudinal incisions 9 which are particularly useful in preventing side slipping. In Fig. 4, incisions 10 are shown set at an angle at approximately 45 degrees to the longitudinal center of the sole and heel 11. Such incisions combine certain of the advantages of the transverse incisions in preventing back slipping and certain of the advantages of the longitudinal incisions in preventing side slipping of the shoe.

In Fig. 5 a double diagonal arrangement of incisions 12 and 13 is illustrated. The intersections of the incisions 12 and 13 break the wearing surface up into a plurality of square blocks which are flexible relative to each other so that

they move slightly while maintaining their grip on the ground surface thereby reducing scuffing to a greater degree than do the arrangements shown in the previously described figures.

5 A transverse serrated path is formed by the blocks' intersecting sides lying next to and intersecting a transverse line extending generally in the transverse direction and passing through diagonally opposite corners of several adjacent 10 blocks. The several serrated paths so formed are of course longer than the paths formed by straight slits shown in Figs. 1 to 3 and when the sharp corners of the slits in the serrated paths tilt up under the pressure of the foot wearing the 15 shoe, a greater length of the gripping edge is exposed to the supporting surface.

Referring to Fig. 6, there is shown a combined sole and heel 14 in which longitudinally extending grooves 15 are originally molded. If desired 20 the grooves 15 may extend through the margin of the surface of the tread of the sole and heel portion. Transverse incisions 16 intersect the grooves 15 so that relatively short pads are provided for squeezing out the liquid film from 25 between the rubber surface and the pavement. Such a design of the combined sole and heel is particularly useful for very heavy service boots such as hunting and miners' boots.

Fig. 7 illustrates a sole 17 having transverse 30 incisions 18. Fig. 8 illustrates a heel 19 having transverse incisions 20, made within the outer margin 21, and Fig. 9 illustrates a heel provided with longitudinal grooves or slots 22 and transverse incisions 23 which extend entirely across 35 the face of the heel and through the outside margin. In Fig. 9 a circular groove 24 is formed in the face of the heel within which an insignia may be placed. The heels illustrated in Fig. 8 and Fig. 9 may be secured to the shoe by nails 40 extending through holes, such as the holes 25 shown in Fig. 9.

By applying the incisions to heels the jar experienced with walking is materially reduced as 45 the sub-sections of the wearing surface are free to adjust themselves to the inequalities of the worn heel or ground surface and/or load so that a more uniform overall pressure is obtained than is usually obtained where a less flexible body of rubber is employed for the heel.

50 While I have illustrated and described several designs or patterns of incisions, it will be understood that other patterns may be used within the spirit of the invention and with equally good results. The several modifications of the invention 55 are all characterized by the application of incisions, either so narrow as to be substantially invisible, or so that the opposite walls normally engage, which result in squeezing of a liquid film from between the rubber surface and the ground 60 thereby insuring a better contact between the rubber surface and the ground surface. Such constructions are particularly useful where the footwear is used in wet and slimy places. The application of the invention to heels also reduces 65 the jarring. By reason of the subdivision of the wearing surface into small units, these units are free to flex slightly and accommodate themselves to unevennesses in the ground surface or inequalities of the imposed load without slipping or 70 scuffing thereby giving the footwear better wearing characteristics.

The flexing action is advantageous in wet places, because when the tread surface is applied to a wet supporting surface, a film of liquid is between the two surfaces and reduces the friction

therebetween. The tendency of the tread surface to move over the supporting surface, under the pressure of the foot, causes the sections of the tread surface between the incisions to tilt up as they flex and expose the relative 5 sharp corners of the sections along the edges of the incisions to the supporting surface. This action brings the corners or sharp edges of the incisions in direct contact with the supporting surface to provide gripping surfaces and forms 10 recesses between the tilted up tread sections and the supporting surface for the film of liquid to be squeezed into. The various patterns of incisions may be made in a sole and/or heel having a smooth or uneven surface, examples of the latter 15 are the grooves 15 in Fig. 6, or they may be made in surfaces having various designs.

While I have shown and described present preferred embodiments of my invention, it is to be understood that the invention may otherwise be 20 embodied within the spirit thereof and the scope of the appended claims.

Having thus described my invention, what I claim and desire to protect by Letters Patent is:

1. In a shoe, a vulcanized flexible rubber composition tread having a tread surface provided with a multiplicity of incisions so as to provide individual tread sections having tread surfaces, the walls of said incisions being normally in contact and the tread surfaces of said sections presenting a substantially continuous surface when the tread is at rest, said incisions extending inwardly from said tread surface but leaving an uncut base integral with the sections, and said incisions being of such a spacing and depth as to 30 enable the tread sections to flex on the uncut base to an extent to tilt up and expose the corners of the sections when the foot wearing the shoe and applying weight on the tread surface tends to slip upon some desired supporting surface with which the tread surface is in contact.

2. In a shoe, a vulcanized flexible rubber composition tread having a tread surface provided with a multiplicity of incisions made without the substantial removal of any of the rubber composition so as to provide individual tread sections having tread surfaces, the walls of said incisions being normally in contact and the tread surfaces of said sections presenting a substantially continuous surface when the tread is at 45 rest, said incisions extending inwardly from said tread surface but leaving an uncut base integral with the sections, and said incisions being of such a spacing and depth as to enable the tread sections to flex on the uncut base to an extent to 50 tilt up and expose the corners of the sections when the foot wearing the shoe and applying weight on the tread surface tends to slip upon some desired supporting surface with which the tread surface is in contact.

3. In a shoe, an outsole of elastic cushion rubber having a tread surface provided with a multiplicity of slits extending generally transversely of the shoe and providing tread sections, the surfaces of said tread sections formed by said slits being normally in contact when the outsole is at rest, said slits extending inwardly but partially to leave an uncut base integral with the sections, and said slits being of such a spacing and depth as to enable the tread sections to flex on the uncut base of the outsole to an extent to 65 tilt up and expose the corners of the sections when the foot wearing the shoe and applying weight on the tread surface tends to slip upon 70

some desired supporting surface with which the tread surface is in contact.

4. In a shoe, an outsole of elastic cushion rubber having a tread surface provided with a multiplicity of generally uniformly spaced slits extending generally transversely of the shoe and providing tread sections of generally similar width, the surfaces of said tread sections formed by said slits being normally in contact when the outsole is at rest to present a smooth outer tread surface at the juncture of said sections free from any recesses, said slits extending inwardly but partially to leave an uncut base integral with the sections, and said slits being of such a spacing and depth as to enable the tread sections to flex on the uncut base of the outsole to an extent to tilt up and expose the sharp corners of the sections when the foot wearing the shoe and applying weight on the tread surface tends to slip upon some desired supporting surface with which the tread surface is in contact.

5. In a shoe, an outsole of elastic cushion rubber having a tread surface provided with a multiplicity of slits extending generally transversely of the shoe and providing tread sections, the surfaces of said tread sections formed by said slits being normally in contact when the outsole is at rest, said slits forming serrated paths trans-

versely across the shoe and extending inwardly but partially to leave an uncut base integral with the wavy sections, and said slits being of such a spacing and depth as to enable the tread sections to flex on the uncut base of the outsole 5 to an extent to tilt up and expose the corners of the sections when the foot wearing the shoe and applying weight on the tread surface tends to slip upon some desired supporting surface with which the tread surface is in contact. 10

6. In a shoe, an outsole of elastic cushion rubber having a tread surface provided with a multiplicity of slits extending generally transversely of the shoe and providing tread sections, the surfaces of said tread sections formed by said slits 15 being normally in contact when the outsole is at rest, said slits extending inwardly but partially to leave an uncut base integral with the sections, and said slits being of such a spacing and depth as to enable the tread sections to flex 20 on the uncut base of the outsole to an extent to tilt up and expose the corners of the sections when the foot wearing the shoe and applying weight on the tread surface tends to slip upon some desired supporting surface with which the 25 tread surface is in contact, the peripheral edge presenting an uncut area.
